UNITED STATES PATENT OFFICE

144,007

DESIGN FOR A COMBINATION NAIL FILE AND POLISH RECEPTACLE

Henry Troya, Inglewood, Calif.

Application May 7, 1945, Serial No. 119,437

Term of patent 14 years

(Cl. D86—10)

To all whom it may concern:

Be it known that I, Henry Troya, a citizen of the United States of America, residing in the city of Inglewood, in the county of Los Angeles, State of California, have invented a new, original, and ornamental Design for a Combination Nail File and Polish Receptacle, of which the following is a specification, reference being had to the accompanying drawing, forming a part thereof.

Fig. 1 is a top plan view of a combination nail file and polish receptacle, showing my new design;

Fig. 2 is a front elevational view of the same;
Fig. 3 is an elevational view of one side of the device;

Fig. 4 is an elevational view of the other side of the device; and

Fig. 5 is a perspective view thereof.

I claim:

The ornamental design for a combination nail file and polish receptacle, substantially as shown.

HENRY TROYA.
